UNITED STATES PATENT OFFICE.

ALBERT R. LARRABEE, OF JERSEY CITY, NEW JERSEY.

DISPLAY-CARD.

1,141,349.

Specification of Letters Patent.

Patented June 1, 1915.

Application filed September 10, 1914. Serial No. 860,993.

To all whom it may concern:

Be it known that I, ALBERT R. LARRABEE, a citizen of the United States, residing at Jersey City, in the county of Hudson and 5 State of New Jersey, have invented certain new and useful Improvements in Display-Cards, of which the following is a specification.

My invention relates to cards adapted to 10 display and analogous uses, and has for its essential objects economy of space, cheapness of construction, firmness of engagement, and accessibility.

To the above ends essentially my invention 15 consists in such parts and combinations of parts as fall within the scope of the appended claims.

In the accompanying drawings which 20 form a part of this specification, Figure 1 is a front elevation of my display card showing two cards or photos mounted thereon, Fig. 2, a rear elevation of a lateral portion of the same, Fig. 3, a section on line α , α , of Fig. 1, and Figs. 4 and 5, detail views 25 of the engaging members or clips.

Like reference characters indicate like parts throughout the views.

A represents a body or backing of cardboard or other material of any convenient 30 shape, but preferably square or oblong, and provided with a perforation α at its central upper portion adapted for suspension purposes. Spaced upon its lateral edges are 35 cavities or openings b . Parallel with each series of cavities is a series of holes c in the lateral margins of the body, each hole being in horizontal alinement with the adjacent cavity, and with a corresponding hole upon the opposite margin. A string, thread, filament or like member D is applied to the 40 holes and cavities of each side of the display card as follows: The string is passed by a series of manipulations through the holes c and the cavities b in a series of horizontal loops d , so that the intersections of the material at the closed ends of the loops occurs in the cavities b , whence the portions 45 e of the string that is continued from the intersections pass along the edge of the card to the next adjacent cavity. The loops d are preferably drawn sufficiently loose to admit the application thereto of clips, holds, or suspension members F, which in the 50 present instance are U-shaped in form consisting of an arched portion f and two par-

allel arms f' . One arm f' has an opening g near its lower end, and the other arm has an integral projection or prong g' adapted to register in the opening g when the arms are bent toward and into contact with each other. The member F is preferably of bendable material and may if desired be provided in its arched end portion f with a V-shaped opening h . Upon each loop d is suspended one of the members F, the former 60 passing between the legs of the latter member and in contact with the concave face of the portion f . It will be observed that each suspension member is capable of pivotal movement upon its loop or suspension 65 filament d , and further that the respective members of each of the two marginal series of suspension members are in horizontal alinement with each other so as to adapt them for engaging the articles to be suspended near the end portions of the latter and to hold the same in perfect horizontal alinement.

In the drawings are shown two cards or 70 photographs H attached to the members F. 80 To insert a card or other article in the members the arms f' are normally distended at their ends and the margin of the card is inserted intermediate the legs upwardly to a point adjacent the portion f of the suspension member, and then the legs are manually pressed together to bring the prong g' into or through the opening g , and through the material of the card, thus firmly engaging 85 the latter.

It will be observed that the suspended 90 cards H overlap each other in a series as suggested by Figs. 1 and 3, wherein only two cards are shown attached for the purpose of illustration. The lower margins of 95 these cards are spaced from each other, and are at an inclination so as to be readily accessible; and when it is desired to examine the face of an intermediate card the pivotal character of the members F permit all the 100 cards above the desired card to be readily swung upwardly, simultaneously against the face of the body A, and immediately disclose the card being examined. By this arrangement furthermore a maximum number 105 of cards may be arranged in a minimum space and the cost of construction of the device is small.

What I claim is:

1. In a display card, a body having a plu- 110

rality of longitudinal series of holes and marginal cavities, and a plurality of transversely-disposed loops formed from a filament engaged in said holes and cavities.

5 2. In a display card, a body having a plurality of longitudinal series of holes and marginal cavities, a plurality of transversely-disposed loops formed from a filament engaged in said holes and cavities, and suspending members pivotally mounted in said loops.

10 3. In a display card, a body provided with a plurality of longitudinal series of holes adjacent an edge thereof and with 15 cavities in said edges, the holes and cavities being in alinement with each other, and a filament engaged in said holes and formed into loops with the material at the closed ends of the loops disposed in said cavities.

20 4. In a display card, the combination of a body provided with a plurality of longitudinal series of holes, transverse loops formed from a filament passing through the holes with portions of the filament extended

along the edge of said body, and suspension 25 members pivotally mounted on the loops.

5. In a display card, the combination of a body provided with longitudinal series of holes upon its lateral margins, and cavities in its lateral edges in transverse alinement 30 with the holes, loops registering in the holes and cavities formed from a continuous filament, and suspension members pivotally mounted on the loops.

6. In a display card, the combination of a 35 body provided with series of marginal holes, and with cavities in its edges adjacent the holes and in alinement therewith, loops formed from a continuous filament passing through the holes, said loops having their 40 closed ends located in the cavities, and suspension members mounted in the loops.

In testimony whereof I have affixed my signature in presence of two witnesses.

ALBERT R. LARRABEE.
